PANEL ATTACHING DEVICE

Frederick M. Small, York, Pa., assignor to Martin-
Parry Corporation, York, Pa., a corporation of
Delaware

Application April 8, 1939, Serial No. 266,892

8 Claims. (Cl. 189—88)

This invention relates to panel attaching devices and more particularly to devices for attaching panels to walls or other structures so that the attaching device is entirely concealed by the panels.

An object of the invention is to provide an improved attaching device which is readily installed and which cooperates with a panel designed to receive the same to secure the panel to a wall structure.

A further object of the invention is to provide an attaching device which does not require drilling or other work to be performed upon the panel during installation and which is concealed by the panel.

A still further object is to provide a device for attaching panels to preformed metallic studs or furring strips without the necessity of boring holes therein or employing the usual securing members such as nails or screws.

Other objects and advantages of the invention will appear in the following description of the attached drawings of which:

Figure 1 is an elevation of a portion of a device employed in attaching panels to wood studs;

Figure 2 is a horizontal section through a complete device in accordance with Fig. 1 showing the panels in position;

Figure 3 is a vertical section on the line 3—3 of Fig. 2 also showing a third panel at right angles to the panels shown in Fig. 2;

Figure 4 is a view similar to Fig. 2 of another form of the invention upon an enlarged scale;

Figure 5 is a fragmentary view in horizontal section of a modified fastening device;

Figure 6 is a fragmentary view of a locking member for the device of Fig. 5;

Figure 7 is a horizontal section of the fastening device of Fig. 5 applied to a furring strip, and

Figure 8 is a view similar to Fig. 7 showing a modified fastening device applied to a metal stud.

The device of Figs. 1 to 4 is particularly adapted for fastening panels to wooden wall structures and includes bridging members 10 adapted to extend between studs one of which is indicated at 11. Preferably the spacing between the center lines of the studs 11 is the same as the width of the panels employed and the bridging members 10 are also of the same length as the width of the panels.

As shown in Fig. 3 the spacing members 10 are preferably of channel cross section between studs and terminate in flat end portions 12 provided with upstanding lugs 13 having laterally extend-

ing portions 14 parallel to the flat portions 12 as shown more clearly in Fig. 2. The flat portions 12 are provided with integral portions 15 adjacent the sides thereof which overlap similar portions 15 of an adjacent bridging member 10. The portions 15 of the adjacent bridging members 10 are provided with aligned apertures through which a fastening member such as a screw 16 may be inserted to fasten the bridging members to the stud 11. As shown in Figs. 2 and 4 a clip 17 is positioned upon the lugs 13 and held thereupon by the laterally extending portions 14 of the lugs 13 and extends into channels 18 provided in panels 19. 5 In installing panels by the attaching means shown in Figs. 1 to 4, a panel is first positioned against the bridging members 10, and a clip 17 inserted in the channel 18 of the panel and slipped downwardly over the lugs 13 of the bridging members. A second panel is then applied by 10 sliding the same laterally so that a channel 18 thereof embraces the clip 17 and then another clip is inserted in the channel 18 of the other edge of the second panel. Since the length of 15 the bridging members 10 is equal to the width of the panel, the lugs 13 and clip 17 are correctly spaced to register with the edges of the panel. It will be noted that the panels 19 are 20 arranged in abutting relationship and entirely conceal the fastening device. It is apparent 25 that the bridging members 10 may be employed for attaching panels to other structures than the wooden structures shown, for example, the surfacing material of a wall or ceiling. 30 35 In Fig. 3 I have also disclosed a means for attaching a panel 20 positioned at right angles to the panels 19 so as to cover the ends of the panel 19. Such a structure may be employed where a horizontal panel adjacent the ceiling or floor is desired. In this structure a member 21 may be inserted into a hollow portion 22 (see 40 also Fig. 2) running longitudinally of the panel 19 so that an end of the member 21 projects into the channel 18 of the panel 20. 45 A preferred panel 19' is shown in more detail in Fig. 4 and includes a sheet metal envelope 23 surrounding a filler member 24, which may be formed of corrugated sheet metal, and a supplemental sheet metal member 25 attached to the 50 envelope 23 at 26 and having a portion 27 gripping the edge of the filler member 24. The panel 19' of Fig. 4 is also provided with channels 18 for receiving the clip 17 in the same manner as the panel disclosed in Figs. 1 to 3. 55 The structure disclosed in Fig. 7 for attaching

the panels 19' to a metal furring strip 28 includes lug members 29 having portions 30 extending rearwardly of the edges 31 of the furring strip 28. The edges of the furring strip are preferably inclined rearwardly as shown in Fig. 7 so that the lug members 29 are clamped in position upon the furring strip by the U shaped member 32, more clearly shown in Fig. 6, which embraces the lugs 33 of the lug members 29. As shown most clearly in Fig. 5 the lugs 33 are formed with laterally extending portions 34 for retaining the U shaped member 32 in position. The lugs 33 are also provided with laterally extending portions 14 for receiving a clip 17 in the same manner as the structure shown in Figs. 1 to 4. The clip 17 extends into the channels 18 of the panel 19' to retain the channel in position against the furring strip 28.

In Fig. 8 I have shown a modification of the device of Fig. 7 which can be employed to secure the panels to metal studs. The cross section of a portion of such a stud is shown in Fig. 8 and is provided with channels 35 partly closed by portions 36 around which the hooked end portions 37 of a lug member 38 are engaged. The lug members 38 are provided with lugs 33, laterally extending portions 34 for retaining the U shaped clamping member 32 in position and laterally extending members 14 for holding the clip 17 of Fig. 7. The clip 17 for attaching the panels are applied to the lug members 38 of Fig. 8 in exactly the same manner as they are applied in Figs. 1 to 7.

It will thus be seen that I have provided an attaching device for fastening panels to a wall or other structure by which the fastening devices are completely concealed by the panel and which may be installed with a minimum of labor. The essential features of all of the modifications of the fastening devices are the same and by slight modifications panels may be attached to any type of wall structure including prefabricated metal studs or furring strips. No operations such as drilling or the insertion of screws or nails are required and it is merely necessary to assemble the fastening devices and panels with the wall members. In this latter construction the panels themselves are ordinarily employed as the means for spacing the studs or furring strips. A furring strip or stud is installed, a panel is then fastened thereto and a second furring strip or stud installed against the opposite edge of the panel but this procedure may be varied by installing the studs and panels a proper distance apart.

While I have disclosed the preferred embodiments of my invention it is understood that the details thereof may be varied within the scope of the following claims.

I claim:

1. A device for attaching panels having channels in the edge thereof to a supporting structure, said device comprising a pair of attaching members engaging opposite sides of a wall frame member, said attaching members having extensions forming bridging extending between adjacent frame members, means for securing said attaching members together to clamp said members against said sides of said frame member and means secured to said attaching members and extending into the said channels of said panels.

2. A device for attaching panels to a supporting structure, said device comprising a pair of

attaching members engaging opposite sides of a frame member of the supporting structure, said attaching members having extensions forming bridging extending between adjacent frame members, means for securing said attaching members together to clamp the same against said sides of said frame member and means for connecting said attaching members to said panels.

10 3. A device for attaching panels to a supporting structure having frame members, said device comprising a pair of attaching members interlocking with the opposite sides of a frame member, said attaching members having extensions 15 forming bridging extending between adjacent frame members, means for securing said attaching members together to maintain the same in contact with said opposite sides of the frame member and means for securing said panels to said attaching members, said panels having a portion covering and concealing said attaching device.

4. A device for attaching panels having recesses in the edges thereof to a supporting structure, said device comprising a pair of attaching members engaging opposite sides of a frame member of the supporting structure, said attaching members having extensions forming bridging extending between adjacent frame members, means for securing said attaching members together to clamp the same against said sides of said frame members, and clip members attached to said attaching members and extending into said recesses to secure said panels to said supporting structure.

5. A device for attaching panels to a supporting structure, said device comprising bridging members extending between frame members of the supporting structure, lug members at adjacent ends of said bridging members, and a clip member 40 embracing adjacent lug members and having portions engaging said panels to secure said panels to said supporting structure.

6. A device for attaching panels having recesses in the edges thereof to a supporting structure, said device comprising, bridging members extending between frame members of the supporting structure, lug members at adjacent ends of said bridging members, and a clip member 50 embracing adjacent lug members and having portions extending into said recesses to secure said panels to said supporting structure.

7. A device for attaching panels to a supporting structure, said device comprising, bridging members 55 extending between frame members of the supporting structure, outwardly extending portions provided at adjacent ends of said bridging members, and means carried by adjacent outwardly extending portions for engaging said panels to secure said panels to said supporting structure.

8. A device for attaching panels having recesses in the edges thereof to a supporting structure, said device comprising, bridging members extending between frame members of the supporting structure, outwardly extending portions provided at adjacent ends of said bridging members, and means carried by adjacent outwardly extending portions and extending into said recesses to secure said panels to said supporting structure.

FREDERICK M. SMALL.
